No. 878,823.

PATENTED FEB. 11, 1908.

W. W. McNAUGHTON.
STATIONERY NOVELTY.
APPLICATION FILED JULY 5, 1907.

UNITED STATES PATENT OFFICE.

WILLIAM W. MCNAUGHTON, OF NEWARK, NEW JERSEY.

STATIONERY NOVELTY.

No. 878,823.

Specification of Letters Patent.

Patented Feb. 11, 1908.

Application filed July 5, 1907. Serial No. 382,161.

To all whom it may concern:

Be it known that I, WILLIAM W. MCNAUGHTON, a citizen of the United States, residing at Newark, in the county of Essex and State 5 of New Jersey, have invented certain Improvements in Stationery Novelties, of which the following is a specification.

The objects of my invention are to provide a small attractive article which can be 10 worn upon a chain and provide within itself a scroll of paper or strip of stamps and a pencil or a stick of sealing wax, as well as a seal upon one end; to enable the pencil or sealing wax to be concealed until needed; to enable the 15 device to accommodate itself to different sized rolls of paper or stamps; to secure a simple and inexpensive construction, and to obtain other advantages and results as may be brought out in the following description.

20 Referring to the accompanying drawings, in which like numerals of reference indicate corresponding parts in each of the several figures, Figure 1 is a perspective view of my improved device showing a strip of stamps 25 partly drawn out; Figs. 2 and 3 are side elevations illustrating certain sealing wax and pencil attachments, respectively; Fig. 4 is a central longitudinal section of the body of the device; Fig. 5 is a perspective view of a 30 certain resilient casing; Fig. 6 is a perspective view of a tubular spindle, and Fig. 7 is a sectional view taken on line z , Fig. 2, looking in the direction indicated by the arrow.

My invention may be secured to a watch 35 chain or other chain, by either ladies or gentlemen, attached to a key ring and carried in the pocket, or used in any other way, and provides a convenient article to hold stamps or a strip of paper, a pencil, or seal and sealing- 40 wax, at times or places where such things cannot readily be had otherwise.

In said drawings, 1 indicates a ring which 45 can be fastened to a chain or key-ring and is secured to a head or cap 2 provided with a reduced threaded portion 3 adapted to screw into the end of a tubular spindle 4. At the 50 opposite end of said spindle is another cap 5, similar to cap 2, secured therein by means of its reduced threaded portion 6, said 55 threads being of the opposite hand from the threads on cap 2, so as to prevent the cap 5 from unscrewing when the said cap 2 is unscrewed. Obviously this might be prevented in other ways, as by making a cap in one 55 piece with the spindle, soldering it in place, or otherwise fixing it to the spindle.

The unscrewing of the cap 2 is necessary in order to utilize a pencil 7 or stick of sealing wax 8, either of which may be secured endwise upon the reduced threaded portion 3 of 60 the cap, as shown in the drawings, and normally concealed in the hollow spindle 4. When sealing wax is employed in my device, the outer end surface 9 of the cap 5 may be engraved or inscribed, as at 10, to provide a 65 seal or stamp to form an impression in the said wax when soft.

A resilient cylindrical casing 11 is mounted 70 between the said end caps 2 and 5, abutting thereagainst at its ends and inclosing the hollow spindle 4, at a distance therefrom. At the ends of this casing 11, which is preferably of light sheet metal, are lugs 12 bent radially inward and adapted at their extremities to engage the spindle 4 and hold the cas- 75 ing away from the same to provide a uniform chamber 13. I have shown three such lugs, although more might be used. Said casing 11 is longitudinally slotted, as at 14, to provide for the entrance or egress of a strip of 80 paper 16 or stamps 17, to or from the annular chamber between the spindle 4 and casing 11. For attaching the inner end of a strip to said spindle, the same is longitudinally slotted as at 15 to permit the end of the strip to be inserted therein, and this insertion is accomplished by holding the resilient casing 11 while the spindle 4 is turned to bring its slit 15 in line with the slot or mouth 14 of the casing. The end of a strip of stamps or 90 paper may then be passed through the slot or mouth 14 and inserted into the said slit 15 of the spindle 4; when by turning the said spindle by means of its end caps, the strip is wound on the outside of the spindle and within the said chamber 13 until the roll 18 is complete.

Preferably, to facilitate the winding of the strip, the exterior of the spindle is left rough or unfinished, while the interior of the casing 11 is finished smooth or nickelized like its exterior. If the strip is very long and would form a roll larger than the space provided in the chamber 13, the resilient casing 11 will expand and provide a larger chamber to 100 accommodate the roll. At the same time, when the roll is reduced or exhausted, the casing will close its lugs 12 against the spindle 4 and prevent any looseness or rattling. 105

In the operation of my improved device, it will be understood, the casing 11 is held by the fingers of one hand, and one of the caps 2,

5 is grasped and revolved by the fingers of the other hand, when the strip of paper or stamps will unwind and pass out through the opening or slot 14, as shown in Figs. 1 and 7. 5 It will also be understood that the device can be made up either expensively as of gold, silver or the like, or it can be manufactured cheaply as by stamping and nickelizing. In 10 the latter case, the device can be readily adapted to use as an advertising medium, by printing upon the outer surface of the casing or the like.

Obviously various detail modifications and changes could be made from the construction 15 especially shown and described, without departing from the spirit and scope of the invention, and I do not wish to be understood as limiting myself by any positive descriptive terms herein employed except as the state of 20 the art may require.

Having thus described the invention, what I claim as new is:

1. In a device of the character described, the combination of a tubular spindle with open 25 ends, end caps having stems adapted to enter the opposite open ends of said spindle and detachably connect therewith by turning in opposite directions and having heads enlarged radially beyond the said spindle, and a split 30 tubular casing inclosing said spindle, having its ends closed by said caps and being free to turn.

2. In a device of the character described, the combination of a central spindle, radially 35 projecting caps on the opposite ends of said spindle, and a tubular casing of resilient sheet metal with open ends and split for its entire length arranged on said spindle between said end caps and free therefrom to ex-

pand and contract with respect to the spindle, its ends being closed by said caps.

3. In a device of the character described, the combination of a central spindle, radially projecting caps on the opposite ends of said spindle, and a cylindrical casing on said spindle between said end caps having at its end edges lugs turned radially inward and adapted 45 to engage the spindle and hold said casing in axial coincidence therewith.

4. In a device of the character described, the combination of a central spindle, radially projecting caps on the opposite ends of said spindle, and a split cylindrical casing of resilient sheet material on said spindle between said end caps and separate therefrom, said 55 casing having at its ends integral lugs bent radially inward and adapted to engage the spindle.

5. A device of the character described, comprising a hollow spindle having one end 60 interiorly threaded, end caps at the opposite ends of said spindle one having an engraved outer end surface and the other a reduced extension threaded to screw into said threaded end of the spindle, a stick of sealing wax 65 mounted on said last-mentioned cap in endwise alinement with its said reduced extension and adapted to enter the hollow spindle or be removed therefrom with its end-cap, and a cylindrical casing on said spindle between 70 said end caps held thereby against movement longitudinally but free to move otherwise with respect thereto.

WILLIAM W. McNAUGHTON.
